HAND ABRADER

Anker W. Jensen, Oak Park, Ill.

Application May 10, 1946, Serial No. 668,677

11 Claims. (Cl. 51—186)

This invention relates to a hand abrader for abrading or sandpapering various surfaces including the surfaces of articles of furniture and the like.

An object of the invention is to provide a simple and relatively inexpensive hand abrader or so-called sandpapering device for use in sandpapering which is so constructed and arranged that all of the parts of the available abrasive surface on a continuous web of sandpaper or like abrasive paper may be utilized successively by adjustment of the parts embodied in the new hand abrader or sandpapering device.

Another object of the invention is to provide in the new hand abrader or sandpapering device a novel construction and arrangement for tensioning the continuous web of sandpaper or like abrasive material upon and relative to the supporting frame which is embodied in the new hand abrader.

A further object of the invention is to provide a novel construction and arrangement for effecting manual adjustment of the sandpaper or abrasive web upon and relative to the supporting frame of the new hand abrader or so-called sandpapering device.

Other and further objects of the present invention will be apparent from the following description and claims and are illustrated in the accompanying drawing which, by way of illustration, shows a preferred embodiment of the present invention and the principles thereof and what I now consider to be the best mode in which I have contemplated applying these principles. Other embodiments of the invention embodying the same or equivalent principles may be used and structural changes may be made as desired by those skilled in the art without departing from the present invention and the purview of the appended claims.

In the drawings:

Fig. 1 is a side elevational view of a hand abrader embodying the present invention;

Fig. 2 is a top plan view of the hand abrader shown in Fig. 1;

Fig. 3 is a central longitudinal vertical sectional view on line 3—3 in Fig. 2;

Fig. 4 is a transverse vertical sectional view on line 4—4 in Fig. 1;

Fig. 5 is a transverse vertical sectional view on line 5—5 in Fig. 1; and

Fig. 6 is a fragmentary detail view on line 6—6 in Fig. 5.

A preferred embodiment of the new hand abrader or so-called sandpapering device is ill-

ustrated in the drawing wherein it is generally indicated at 10 and comprises a main supporting frame 11 which is substantially rectangular in shape and includes a top wall 12, a bottom wall

13 and end walls 14 and 15. As shown in Fig. 3, the top wall 12 of the main supporting frame member 11 has an end portion 16 which is bent downwardly at one end of the supporting frame 11, and this end portion 16 has a centrally arranged notch or recess 34 formed therein (Figs. 4 and 5). The bottom wall 13 has an upwardly extending end portion 35 and this end portion 35 has a centrally arranged tongue portion 36 which projects into and is slidably interfitted with a correspondingly shaped notch or recess 34 in the depending end wall portion 16 of the top wall 12. Thus, the parts 16—34—35 and 36 cooperate to form the end wall 14 of the supporting frame 11.

The end wall 15 of the supporting frame 11 is formed in a similar manner but in this instance the bottom wall 13 has an upward extension 19 which is provided with a centrally arranged notch or recess 37 which corresponds to the recess 34. The top wall 12 of the supporting frame 11 has a depending end portion 18 which is provided with a centrally arranged tongue 38 (Fig. 3) and this tongue 38 extends into and is slidably interfitted with the notch or recess 37 in the end wall portion 19. Thus the parts 18—19—37 and 38 cooperate to form the end wall 15 but the arrangement of the parts 18—19—37—38 in the end wall 15 is complementary or opposite to the arrangement of the parts 16—34—35—36 in the end wall 14 of the supporting frame 11.

The top wall 12 has a portion 20 partially struck therefrom at each side thereof and each of these partially struck out portions 20 provides an opening 21 which extends parallel to the long axis of the supporting frame 11 at the side thereof and throughout the major portion of its extent (Fig. 2).

As shown in the drawing (Fig. 2) each of the parts 20 which are partially struck from the top wall 12 of the supporting frame 11 is integrally attached at each end, as at 39, to a corner portion 40 of the top wall 12. As shown in Fig. 2, the inner ends of these corner portions 40 define the end walls of the slots 21.

It will thus be seen that the parts 20, as shown in Figs. 4 and 5, project partially above and partially below the top wall 12 of the supporting frame 11 and project outwardly beyond the side edges of the supporting frame 11, for a reason which will be explained hereinafter.

The bottom wall 13 of the supporting frame 11

has parts 22 formed therein and these parts 22 are similar to the parts 20 formed in the top wall 12 and provide or form slots 23 in the bottom wall 13 which correspond to the slots 21 in the top wall 12 of the supporting frame (Fig. 4).

The new hand abrader or sandpapering device includes a pair of adjustable clamping side plates or members 27, each of which includes a main side wall portion 28. A pair of inwardly extending flanges 41 are formed on each of the side wall clamping plates 28, one at each end thereof, as shown in Figs. 4, 5 and 6, and these inwardly extending flanges 41 are frictionally engaged with the inner surfaces of the end walls 14 and 15 of the main supporting frame 11.

As shown in Figs. 4 and 5, each of the adjustable clamping side plates 27-28 has an outwardly and upwardly flared or extending clamping flange 30 formed at the top thereof and a corresponding outwardly and downwardly flared or extending clamping flange 30 formed at the bottom thereof. Each of the upper clamping flanges 30 is adapted to bear against and to have clamping engagement with the outer surface of one of the flanges 20 formed in the top wall 12 of the supporting frame 11 and each of the lower clamping flanges 31 is adapted to have clamping engagement with the outer surface of one of the lower clamping flanges 22 formed on the bottom wall 13 of the supporting frame 11.

Each of the adjustable side clamping plates 28 has a longitudinally extending indentation or recess 29 formed therein, substantially midway between the top and bottom thereof (Figs. 1 and 3) and each of these longitudinally extending indentations or recesses 29 terminates in or merges into a substantially circular-shaped recess or indentation 42. The longitudinally extending indentations or recesses serve as reinforcing ribs to strengthen the adjustable side clamping plates 27-28.

A hole 43 is formed in each of the substantially circular-shaped recesses or indentations 42 and a threaded bolt 32 is extended through each of the holes 43, and to this end the holes 43 and the substantially circular-shaped recesses or indentations 42 in the adjustable clamping side plates 27-28. As shown in Figs. 1 and 4, a wing nut 33 is threaded into the threaded outer end portion of each of the bolts 32 and, as shown in Fig. 4, the wing nuts 33 are disposed largely within the substantially circular-shaped recesses or indentations 42 and inwardly of the outer ends of the clamping flanges 30 and 31 on the adjustable clamping side plates 27-28 so as to facilitate grasping the new hand abrader or sandpapering device in the hand of the user.

A washer 44 is arranged on the outer end portion of each of the bolts 32 between the wing nut 33 and the outer surface of the wall of the corresponding substantially circular-shaped recess or indentation 42.

A pad or cushion 24 of resilient material such, for example, as sponge rubber, is arranged upon the top wall 12 of the supporting frame 11, between the flanges 20, and a similar pad or cushion 25 of resilient material such, for example, as sponge rubber, is arranged upon the bottom wall 13 between the flanges 22. The resilient pads 24 and 25 may be adhesively or otherwise attached to the top and bottom walls 12 and 13 of the supporting frame 11.

A continuous flexible web or band 26 of abrasive material such, for example, as sandpaper or the like, is extended entirely around

the main supporting frame 11 of the new hand abrader 10 and over the top and bottom resilient pads or cushions 24 and 25 and down over the end walls 14 and 15 on the outer sides thereof.

5 In the use of the new hand abrader the parts of the supporting frame 11 and the adjustable side clamping plates 27-28 and the resilient pads or cushions 24 and 25 may be assembled and arranged in their respective positions in which 10 they are shown in the drawing. A continuous flexible web 26 of sandpaper or like abrasive material may then be arranged upon the device in the manner shown so that it extends over the top of the resilient pad or cushion 24 and over 15 the bottom of the lower resilient pad or cushion 25 and down along the end walls 14 and 15 of the supporting frame 11 on the outer sides thereof. When thus positioned, the flexible abrasive web 26 may be tightened in position of use by 20 adjusting the wing nuts 33 on the bolts 32. This action forces the clamping flanges 30 and 31, which are carried by the adjustable clamping side plates 27-28, against the flanges 20 and 22 which are carried by the top and bottom walls 12 and 13, respectively, of the main supporting frame 11. The pressure of the clamping flanges 30 and 31 against the flanges 20 and 22 urges the top and bottom walls 12 and 13 of the main supporting frame 11 apart, relative to each other, 25 and during this operation the tongue 36 on the end wall portion 35 slides in the notch 34 and the tongue 38 on the end wall portion 18 slides in the notch 37. This movement of the top and bottom walls 12 and 13 of the supporting frame 30 forces the resilient pads or cushions 24 and 25 outwardly against the inner surface of the flexible abrasive web 26 and thus distends the latter and holds it in the desired adjusted position.

35 The hand abrader is then ready for use and is used by the operator by clasping it in his or her hand and moving the outer abrasive coated top or bottom surface of the abrasive web 26 over the surface which is to be abraded or sandpapered.

40 After the abrasive coating has been worn away from the top and bottom outer surfaces of the flexible web 26 a new and previously unused area thereof may be moved into position to be used 50 by loosening the wing nuts 33 on the bolts 32 and adjusting the clamping side plates 27-28 so as to move the clamping flanges 30 and 31 out of engagement with the flanges 20 and 22, respectively. The flexible abrasive web 26 may then be 55 moved around and relative to the supporting frame 11 so as to move another and previously unused portion or area of the flexible abrasive web 26 into position of use. The flexible abrasive web 26 may then again be secured in position of use by tightening the wing nuts 33 on the bolts 32 so as to move the clamping flanges 30 and 31 into clamping engagement with the flanges 20 and 22, respectively, and thus move 60 the upper wall 12 and the lower wall 13 of the main supporting frame 11 against the resilient pads 24 and 25, respectively. As pointed out hereinbefore, this urges the resilient pads 24 and 25 against the inner and uncoated surface of the abrasive web 26 and thus secures the same 65 in the desired adjusted position ready for use. This operation may be repeated until substantially all of the abrasive coated area of the flexible abrasive web 26 has been utilized, thus effecting an economy in the use of the flexible abrasive 70 coated paper web 26.

It will be understood, in this connection, that in order effectively to use a hand abrader of the character contemplated by the present invention, it is possible to use at any one time only the outer abrasive coated surface which extends over the top of the upper resilient pad or cushion 24 on the abrasive coated surface which extends below the bottom surface of the bottom resilient pad or cushion 25 since it is not possible effectively to use these areas or portions of the flexible abrasive web 23 which extend down over the end walls 14 and 15 on the outer sides thereof.

It will thus be seen from the foregoing description, considered in conjunction with the accompanying drawings, that the present invention provides a new and simple and relatively inexpensive hand abrader or so-called sandpapering device having the desirable advantages and characteristics and which accomplishes its intended objects, including those hereinbefore pointed out and others which are inherent in the invention.

I claim:

1. A hand abrader comprising a supporting frame including a top wall and a bottom wall movable relative to and toward and away from each other, a pad of resilient material arranged upon the upper and outer surface of the said top wall and a pad of resilient material arranged upon the lower and outer surface of the said bottom wall of the said supporting frame, a continuous flexible web of abrasive coated material extending around the said supporting frame and over the outer surfaces of the said resilient pads, and means including manually adjustable devices carried by the said supporting frame for urging the said top wall and the said bottom wall of the said supporting frame away from each other so as to urge the said resilient pads carried thereby into engagement with the inner surfaces of the said flexible abrasive-coated web.

2. A portable abrading tool comprising a supporting frame including a pair of substantially parallel walls, a pad of resilient material carried by each of the said substantially parallel walls of the said supporting frame, a continuous flexible web of abrasive-coated material extending around the said supporting frame and over the said resilient pads on the outer surfaces of the latter, and means carried by the said supporting frame and coacting with the said substantially parallel walls thereof for spreading the latter apart so as to urge the said resilient pads carried thereby into engagement with the inner surfaces of the said flexible abrasive-coated web.

3. A hand abrader as defined in claim 1 in which each of the said top and bottom walls of the said supporting frame has a flange formed thereon on each side edge thereof and in which the said means for urging the said top and bottom walls away from each other includes a pair of clamping plates adjustably mounted on the said supporting frame at the sides and between the said top and bottom walls thereof, and in which each of the said clamping plates has a flange formed on each edge thereof and in which each of the said flanges on the said clamping plates is engageable with one of the said flanges on the said top and bottom walls of the said supporting frame for urging the said top and bottom walls apart relative to each other.

4. A hand abrader as defined in claim 1 in which each of the said top and bottom walls of the said supporting frame has a flange formed thereon on each side edge thereof and in which the said means for urging the said top and bot-

tom walls away from each other includes a pair of clamping plates adjustably mounted on the said supporting frame at the sides thereof and in which each of the said clamping plates extends substantially vertically between the said top and bottom walls of the said supporting frame, and in which each of the said clamping plates has a flange formed on each edge thereof and in which each of the said flanges on the said clamping plates is engageable with one of the said flanges on the said top and bottom walls of the said supporting frame for urging the said top and bottom walls apart relative to each other, and in which each of the said flanges on the said top and bottom walls and each of the said flanges on the said clamping plates extends at an acute angle relative to the vertical extent of the said clamping plates between the said top and bottom walls of the said supporting frame.

5. A hand abrader as defined in claim 1 in which the said supporting frame includes substantially parallel end walls formed by cooperating extensions of the said top and bottom slidably interfitting with each other.

6. A hand abrader as defined in claim 1 in which each of the said top and bottom walls of the said supporting frame has a flange formed thereon on each side edge thereof and in which the said means for urging the said top and bottom walls away from each other includes a pair of clamping plates adjustably mounted on the said supporting frame at the sides thereof and in which each of the said clamping plates extends substantially vertically between the said top and bottom walls of the said supporting frame, and in which each of the said clamping plates has a flange formed on each edge thereof and in which each of the said flanges on the said clamping plates is engageable with one of the said flanges on the said top and bottom walls of the said supporting frame for urging the said top and bottom walls apart relative to each other, and in which each of the said flanges on the said top and bottom walls and each of the said flanges on the said clamping plates extends at an acute angle relative to the vertical extent of the said clamping plates between the said top and bottom walls of the said supporting frame, and in which the said means for urging the said top and bottom walls apart includes a pair of substantially parallel threaded members extending transversely through the said supporting frame and through the said clamping plates, and in which each of the said threaded members has a manually operable

55 threaded member adjustably threaded onto each end portion thereof and in which the said manually operable threaded members are engageable with said clamping plates so as to urge the latter toward each other upon and relative to the said first-named threaded members.

7. A hand abrader as defined in claim 1 in which the said supporting frame is elongated and substantially rectangular in shape and includes a pair of substantially parallel end walls which are substantially shorter in length than the said top and bottom walls and are formed by cooperating and slidably interfitting extensions of the said top and bottom walls.

8. A hand abrader as defined in claim 1 in which each of the said top and bottom walls of the said supporting frame has a flange formed thereon on each side edge thereof and in which the said means for urging the said top and bottom walls away from each other includes a pair of clamping plates adjustably mounted on the

70 said supporting frame at the sides thereof and in which each of the said clamping plates has a flange formed on each edge thereof and in which each of the said flanges on the said clamping plates is engageable with one of the said flanges on the said top and bottom walls of the said supporting frame for urging the said top and bottom walls apart relative to each other.

said supporting frame at the sides and between the said top and bottom walls thereof, and in which each of the said clamping plates has a flange formed on each edge thereof and in which each of the said flanges on the said clamping plates is engageable with one of the said flanges on the said top and bottom walls of the said supporting frame for urging the said top and bottom walls apart relative to each other, and in which the said supporting frame is elongated and substantially rectangular in shape and includes a pair of substantially parallel end walls which are substantially shorter in length than the said top and bottom walls and are formed by cooperating slidably interfitted extensions of the said top and bottom walls, and in which each of the said clamping plates has a substantially vertically and inwardly extending flange formed thereon at each end thereof, and in which each of the said substantially vertically and inwardly extending flanges formed in each of the said clamping plates is frictionally and slidably engaged with the inner surface of one of the said end walls of the said supporting frame.

9. A portable hand abrading tool comprising a supporting frame including a main body and top and bottom supporting walls movable relative to the said main body of the said supporting frame, a resilient member carried by each of the said relatively movable top and bottom supporting walls, a flexible web of abrasive-coated material carried by the said supporting frame and extending over both of the said resilient members on the outer sides thereof, and means including a pair of spaced manually adjustable clamping plates carried by the said supporting frame and movable relative thereto for urging the said relatively movable top and bottom supporting walls and the said resilient member carried thereby away from the said main body of the said supporting frame so as to urge the said resilient members against the said flexible abrasive-coated web on the inner surface thereof.

10. A hand abrader as defined in claim 1 in which each of the said top and bottom walls of the said supporting frame has a flange formed thereon on each side edge thereof and in which the said means for urging the said top and bottom walls away from each other includes a pair of clamping plates adjustably mounted on the said supporting frame at the sides thereof and in which each of the said clamping plates extends substantially vertically between the said top and bottom walls of the said supporting frame, and in which each of the said clamping

plates has a flange formed on each edge thereof and in which each of the said flanges on the said clamping plates is engageable with one of the said flanges on the said top and bottom walls of the said supporting frame for urging the said top and bottom walls apart relative to each other, and in which each of the said flanges on the said top and bottom walls and each of the said flanges on the said clamping plates extends at an acute angle relative to the vertical extent of the said clamping plates between the said top and bottom walls of the said supporting frame, and in which the said means for urging the said top and bottom walls apart includes a pair of substantially parallel threaded members extending transversely through the said supporting frame and through the said clamping plates, and in which each of the said threaded members has a manually operable threaded member adjustably threaded onto each end portion thereof and in which the said manually operable threaded members are engageable with said clamping plates so as to urge the latter toward each other upon and relative to the said first-named threaded members, and in which each of the said clamping plates has a pair of recesses formed therein and in which each of the said manually adjustable threaded members is disposed in one of the said recesses.

11. A portable hand abrading tool as defined in claim 9 in which each of the said top and bottom walls of the said supporting frame has a flange formed thereon on each side edge thereof and in which the said means for urging the said top and bottom walls away from each other includes a pair of clamping plates adjustably mounted on the said supporting frame at the sides and between the said top and bottom walls thereof, and in which each of the said clamping plates has a flange formed on each edge thereof and in which each of the said flanges on the said clamping plates is engageable with one of the said flanges on the said top and bottom walls of the said supporting frame for urging the said top and bottom walls apart relative to each other.
